(57) **CLAIM**

The ornamental design for a cocktail skewer holder, as shown and described.

DESCRIPTION

FIG. 1 is a front perspective view of a cocktail skewer holder showing my new design;
FIG. 2 is a front view thereof;
FIG. 3 is a rear view thereof;
FIG. 4 is a left side view thereof;
FIG. 5 is a right side view thereof;
FIG. 6 is a top view thereof; and
FIG. 7 is a bottom view thereof;
FIG. 8 is a front perspective view of my new design without the cocktail skewers;
FIG. 9 is a front view thereof;
FIG. 10 is a rear view thereof;
FIG. 11 is a left side view thereof;
FIG. 12 is a right side view thereof;
FIG. 13 is a top view thereof; and,
FIG. 14 is a bottom view thereof.
FIGS. 8-14 are shown without the skewers for clarity of illustration.
